MARIMBA

Clair Omar Musser, Evanston, Ill.

Application July 28, 1947, Serial No. 140,554

Term of patent 7 years

(Cl. D56—1)

To all whom it may concern:

Be it known that I, Clair Omar Musser, a citizen of the United States, residing at Evanston, in the county of Cook and State of Illinois, have invented a new, original, and ornamental Design for Marimba, of which the following is a specification, reference being had to the accompanying drawing, forming a part thereof.

In the drawing:

Both sides of the design are substantially the same.

I claim:

The ornamental design for a marimba, substantially as shown and described.

CLAIR OMAR MUSSER.
